(57) **CLAIM**

The ornamental design for an earphone device, as shown and described.

DESCRIPTION

FIG. 1 is a perspective view of an earphone device showing our new design;

FIG. 2 is a front elevational view thereof;

FIG. 3 is a back elevational view thereof;

FIG. 4 is an outer side elevational view thereof;

FIG. 5 is an opposite outer side elevational view thereof;

FIG. 6 is a top plan view thereof;

FIG. 7 is a bottom plan view thereof; and,

FIG. 8 is an inner front elevational view thereof, the inner front elevational view of the other earphone is a mirror image thereof.

The broken lines depict environment that forms no part of the claimed design.
